UNITED STATES PATENT OFFICE.

MANUEL R. RODRIGUES, OF NEW YORK, N. Y.

SUPPORT FOR FOLDING BEDS.

No. 860,941.

Specification of Letters Patent.

Patented July 23, 1907.

Application filed December 29, 1906. Serial No. 349,944.

To all whom it may concern:

Be it known that I, MANUEL R. RODRIGUES, a citizen of the United States of America, and a resident of the borough of Brooklyn, in the city of New York, county 5 and State of New York, have invented certain new and useful Supports for Folding Beds, of which the following is a specification, the same being a full, clear, and exact description of the invention, such as will enable others skilled in the art to which it appertains to make 10 and use the same.

This invention relates to swinging beds, and in particular to devices whereby cot-beds, or like articles, may be sustained either in an open or a closed position in such a manner as to be incapable of being removed 15 from the sustaining wall, etc., and it has for its object the production of an article or apparatus of the class described which will be economical to manufacture and efficient and durable in practical use.

With this object in view the invention consists in 20 certain novel features of construction and arrangement of parts, all of which will be hereinafter described and specifically pointed out in the drawings which accompany and form a part of this specification, and in which

Figure 1 represents a side elevation, partly in section, 25 of a cot-bed and support in which my invention is embodied; Fig. 2 is a side elevation, partly in section, of the same in a closed relation; Fig. 3 is a side elevation, partly in section, of a duplex cot-bed and support arranged according to my invention; Fig. 4 is a plan view 30 of the bed frame; Figs. 5, 6 and 7 are views in detail of my supporting bolts; Fig. 8 is a front elevation of the bolt shown in Fig. 7; and Fig. 9 is a view in section, taken on the line 9, 9, Fig. 7.

Like letters of reference indicate like parts in all the 35 views.

Referring particularly to the drawings, A denotes means for holding a cot-bed, and the like, in a swinging relation, as, in the present embodiment, a hinge-bolt, preferably square in cross section, and formed with an 40 eye a, and wings a⁴, and a flat transverse plate a' to contact the wall, and a threaded shank a². The means I ordinarily use for holding the said hinge-bolt rigidly in position in the interior of the wall consists of a nut C, constructed and arranged to work on the shank a², 45 and also of a washer C' which may be used in connection therewith.

One end of the cot-bed may be sustained by the hinge-bolt A, and I ordinarily employ suitable means for supporting the free end of the cot-bed, as, in the present 50 instance, a bolt B, ordinarily square in cross section, which is formed with wings b⁴, and having a threaded shank b², and a transverse plate b', and has in addition thereto an eye b, and a hook b³.

The frame or frame-work D for supporting the cot- 55 bed, or the like, has ordinarily at the head thereof suitable supporting means, as lugs d², in which are formed

eyes d, and also other and preferably similar supporting means, as a pair of lugs d', located at the foot or ordinarily free end of the same, as is shown in the drawings. The pair of lugs d² are preferably attached in a 60 movable relation to the end of a pair of bolts, as A, by means of pins or pintles, the said lugs and bolts respectively forming the members or leaves of the hinge. Suitable flexible supporting means are ordinarily interposed between the bolts B and the free end of the 65 bed frame in the following manner: One of the ends of a pair of chains E are ordinarily attached to the pair of lugs d', and the other ends of the said chains are preferably engaged with the eyes b of the bolt B. The cot-bed may thus be caused to assume either a horizontal 70 or vertical relation at will, and when the said cot-bed is placed in an upright position, one of the links of each chain near the end thereof and adjacent to the lug d', may be respectively caught on one of the hooks b³ in order to prevent the said cot-bed from being accidentally knocked down.

I sometimes prefer to arrange my cot-beds in a duplex or double series order, as shown in Fig. 3, in which case the bolt A¹⁰ may serve both as a support for the lower cot-bed, and also as a hinge for the upper cot-bed. 80 The said bolt is ordinarily formed with an eye a¹⁰, which serves as one member or leaf of a hinge for the upper cot-bed, a transverse plate a¹¹ to contact the wall face, a threaded shank a¹², and an eye a¹⁴ for the chain of the lower cot-bed, and a hook a¹³ in which the chain 85 of the lower cot-bed may be caught when the said cot-bed is caused to assume a vertical position.

In operation, the front face of the wall is preferably pierced and the bolts A and B inserted therein, after which, openings are cut in the rear face of the 90 wall of sufficient size to permit the retention therein of the rear ends of the shanks of the bolts which are laterally enlarged or provided with means for forming heads on the same, as by attaching the washers and nuts thereto. The said openings are afterwards ordinarily 95 filled with cement, or otherwise securely closed up, whereby the said bolts are rigidly and permanently secured to the wall in an undetachable relation. The bed frame is then ordinarily hinged to the lower bolts and attached by flexible supporting means to the upper 100 bolts as and in the manner hereinbefore set forth.

Inasmuch as these cot-beds are designed to be used, among other places, in prisons, it has been found necessary to construct the bolts so that they cannot possibly be withdrawn, as otherwise, they could be used as 105 weapons, or as means for undermining or otherwise marring or destroying the structure of the cells, and the said bolts are therefore formed with means, as the square shank, or the wings, or both used in combination, whereby the rotary movement of the same in the cement in which they are embedded, is rendered impossible; the withdrawal of the bolts in a longitudinal di-

rection being prevented by the cement and the transverse plates or washers and nuts, by which means the bolts are rigidly and permanently held in position in an undetachable relation.

5 Having thus described and ascertained the nature of my said invention, and in what manner the same is to be performed, it being kept in mind that in law the substitution of equivalents works no variation in the substance of the same, I would have it understood that

10 what I claim as my invention is:

1. In a device of the character described, a bed frame, means secured to a wall for supporting one end of the bed frame and attached thereto in a hinged relation, and consisting of a bolt having a square shank and wings projecting therefrom and one transverse plate resting against one face of the wall, and another transverse plate rigidly held against the inner surface of a recess formed in the wall, and cement applied to said bolt and last-named plate to rigidly and permanently hold the said bolt against rotary and longitudinal movement.

15 2. In a device of the character described, a bed frame, means secured to a wall for supporting one end of the bed frame, and attached to the latter in a hinged relation, and consisting of a body portion, irregular in contour, with 20 axes, at different points along the boundary of a transverse section thereof, of different lengths, and the said body portion being formed with projecting portions to prevent the rotary movement thereof, and having one transverse plate resting against one face of the wall, and an-

other transverse plate rigidly held against the inner surface of a recess formed in the opposite face of the wall, and cement applied to said last named plate to inclose the same and to rigidly and permanently hold the said supporting part against longitudinal movement.

3. In a device of the character described, a bed frame, 35 means secured to a wall for supporting one end of the bed frame, and attached to the latter in a hinged relation, and consisting of a body portion, irregular in contour, with axes, at different points along the boundary of a transverse section thereof, of different lengths, and the said 40 body portion being formed with projecting portions to prevent the rotary movement thereof, and having one transverse plate resting against one face of the wall, and another transverse plate rigidly held against the inner surface of a recess formed in the opposite face of the wall, 45 and cement applied to said last named plate to inclose the same and to rigidly and permanently hold the said supporting part against longitudinal movement, in combination with another practically similar holding means likewise attached to the wall in an undetachable relation; and 50 means for connecting the last named supporting means with the other end of the bed frame.

In testimony of the foregoing specification, I do hereby sign the same in the borough of Brooklyn, in the city, county and State of New York this 18th day of December 55 1906.

MANUEL R. RODRIGUES.
